CORN PAD APPLICATOR

Arthur J. Malavazos, Oakland, Calif.

Application January 3, 1949, Serial No. 68,981

4 Claims. (Cl. 12—103)

1

The present invention relates to a device for locating a corn pad of conventional design within the shoe of the wearer so as to cause the pad to be positioned immediately over the corn when the shoe is placed on the foot.

In the past, it has been common practice to protect corns from the pressure of the shoe by means of well-known types of corn pads formed in the shape of an annular ring, the corn pads being made of a cushioning type of material, such as rubber, felt, etc., with one face of the pad provided with an adhesive coating. In applying the pad, the adhesive is moistened and the pad placed on the toe over the corn and held in place until the adhesive has become set so as to hold the pad in place on the toe. This method of applying corn pads suffers from the disadvantage that the pads must frequently be displaced since the pad comes loose each time the foot is placed in water.

However, in accordance with my invention, I propose to secure the corn pad to the inner surface of the wearer's shoe, in a position immediately above the offending corn, where it will remain for comparatively long periods of time, thereby eliminating the bother and nuisance of repeatedly applying new pads to protect the toe.

Accordingly, it is an object of my invention to provide a method of using corn pads so as to eliminate the necessity for frequent replacement of same.

Another object of my invention is to provide a method for accurately locating a corn pad of conventional design on the inside of the wearer's shoe, immediately above the offending corn.

Another object of my invention is to provide a device for enabling the wearer of the shoe to accurately locate a corn pad within the shoe where it will lie immediately over the corn and protect the same from the painful pressure of the shoe.

Other objects and advantages of my invention are more readily apparent from the following description and the accompanying drawings.

In the drawings:

Figure 1 is a perspective view showing the manner in which the exact location of the corn is marked on the outer surface of the shoe while on the wearer's foot.

Figure 2 is a cross-sectional elevation taken through the toe of the shoe and through the novel device which I have devised for the applying of corn pads to the inner surface of the shoe.

2

Figure 3 is an exploded perspective view which clearly illustrates the component parts of my novel applicator device.

The novel method which I have discovered for enabling corn pads to be secured to the inner surface of the shoe, immediately over the offending corn, consists of marking the location of the corn on the outer surface of the shoe while it is in position on the foot of the wearer, after which the shoe is removed and a needle, or similar small piercing element, is passed through the leather of the shoe from the outside so as to locate the position of the corn on the inner surface of the shoe. A corn pad of conventional construction is then moistened and slipped into the shoe, with the center of the opening in the pad placed over the needle, and the pad then held in place until the adhesive has set. The shoe may then be placed on the wearer's foot and will be found to provide the necessary protection to the corn, and it will further be found that the pad will remain thus positioned within the shoe for an indefinite period of time.

As mentioned earlier herein, I have also devised a novel applying device for facilitating the carrying out of the hereinbefore described method of applying corn pads to the inside of the shoe. As shown in Figures 2 and 3, my novel device consists of a marking and needle-holding element 10 and a pilot element 11 which cooperates with the needle secured in the element 10. The element 10 is provided on one end with a cup-shaped recess 12 so as to form a narrow, annular rim 13 which may be used in marking the location of the corn on the outside of the shoe.

As shown in Figure 1, the element 10 is held in the hand with the end containing the recess 12 held toward the shoe. The exact location of the corn is then ascertained by pressing on the leather of the shoe with the fingers of the other hand, after which the location of the corn is marked on the surface of the leather by pressing the element 10 against the leather and twisting the same back and forth several times so as to provide a circular depression in the leather surrounding the area covered by the corn. In Figure 1 of the drawings, the circular depression thus made is marked by reference numeral 14, while the location of the corn is indicated by the dotted circle bearing reference numeral 15. The shoe is then removed from the foot and a piercing needle 16, which is mounted in the element 10, is then pushed through the material of the shoe in approximately the center of the circle

14, after which the pilot element 11 is thrust into the shoe and placed over the end of the needle 16 projecting through the leather of the shoe. The element 11 is provided with a small hole 17 which is of approximately the same diameter as the needle 16, which hole is slipped over the needle so as to locate the pilot element in the proper position within the shoe.

Any suitable form of retaining means may be provided for frictionally holding the pilot element in place on the needle 16 and, in the present drawings, I have illustrated one possible means for accomplishing this purpose. As shown in Figures 2 and 3, the element 11 is provided with a transverse hole intersecting with the hole 17 at right angles, within which are located a pair of retaining pins 18 which are bevelled on their inner ends so as to cause the pins to be cammed outwardly when the needle is pushed into the hole 17. An annular groove is cut into the pilot element 11, within which groove is placed a snap ring 19 which tends to resiliently urge the pins 18 toward one another. However, the pins may be yieldably forced apart by the needle 16 when the pilot element is placed thereon, after which the bevelled ends of the pins 18 will press against the shank of the needle and maintain the pilot element in place thereon.

After the pilot element 11 has been located in place within the shoe, a corn pad 20 of conventional design is prepared for application by moistening the layer of adhesive 21 thereof, after which the pad is inserted within the shoe and the circular opening 22 therein is slid over the pilot element. The corn pad 20 is then pressed by the fingers up against the leather 23 of the shoe and held in this position until the adhesive has set, so as to finally bind the pad to the inner surface of the leather 23.

After the adhesive has become set, the pilot element 11 is removed from the needle 16 and the needle is withdrawn from the shoe by pulling on the element 10 and the corn pad will now be mounted on the inside of the shoe in such a position as to lie exactly over the corn when the shoe is again placed on the wearer's foot.

The applying device, consisting of the elements 10 and 11, may be made of any suitable material, such as metal, wood, plastic, etc., and will be found to constitute a very simple and inexpensive device for accomplishing the purpose for which it is intended. It is to be realized, of course, that variations in the construction and arrangement of the applicator device may be resorted to without departing from the spirit of my invention.

I claim:

1. A device for locating an annular corn pad on the inside of the wearer's shoe directly around the offending corn comprising means for locating the position of the corn on the outside of the

shoe, a pin mounted in said locating means and adapted to pierce the shoe, and a positioning member so constructed and arranged as to lie within an annular corn pad, said positioning member having a centrally located bore for receiving said pin, whereby the corn pad is caused to lie directly around the corn when the shoe is placed on the wearer's foot.

2. A device for locating a corn pad on the inside of the wearer's shoe directly over the offending corn comprising a cup-shaped marking member for marking the location of the corn on the outside of the shoe, a stylet mounted in said marking member and adapted to pierce the shoe, a pilot member adapted to engage said stylet and so constructed as to guide a corn pad into position on the inner surface of the shoe so as to cause the pad to lie directly over the corn when the shoe is placed on the wearer's foot.

3. A device for locating a corn pad on the inside of the shoe directly around the offending corn, comprising the combination of an annular member for marking the location of the corn on the outside of the shoe, a stylet axially mounted in said annular member for piercing the shoe, and a pilot member for guiding the corn pad into position inside the shoe, said pilot member being provided with a centrally located bore for receiving said stylet when said member is placed in the shoe.

4. A device for locating a corn pad on the inside of a shoe directly over the offending corn comprising a cup member for marking the location of the corn on the outside of the shoe, a stylet mounted in said cupped member for piercing the shoe in accordance with the mark made on the shoe by said cupped member, a pilot member for guiding the corn pad into position inside the shoe, said member being provided with a centrally located bore for receiving said stylet when said member is placed within the shoe.

ARTHUR J. MALAVAZOS.
